(57) **CLAIM**

The ornamental design for a photovoltaic glass roof for vehicles, as shown and described.

DESCRIPTION

FIG. 1 shows a top perspective view of a photovoltaic glass roof for vehicles.

FIG. 2 shows a top plan view of the photovoltaic glass roof for vehicles.

FIG. 3 shows a front elevational view of the photovoltaic glass roof for vehicles.

FIG. 4 shows a rear elevational view of the photovoltaic glass roof for vehicles.

FIG. 5 shows a side elevational view of the photovoltaic glass roof for vehicles, the other side a minor image thereof.

FIG. 6 shows a bottom plan view of the photovoltaic glass roof for vehicles; and,

FIG. 7 shows an enlarged fragmentary cross-sectional view of the photovoltaic glass roof for vehicles taken along line 7-7 of FIG. 2.
